(No Model.)

A. DENNIS.

BACK BAND HOOK.

No. 362,498.

Patented May 10, 1887.

UNITED STATES PATENT OFFICE.

ALBERT DENNIS, OF FRANKLIN, TENNESSEE.

BACK-BAND HOOK.

SPECIFICATION forming part of Letters Patent No. 362,498, dated May 10, 1887.

Application filed February 10, 1887. Serial No. 227,129. (No model.)

To all whom it may concern:

Be it known that I, ALBERT DENNIS, a citizen of the United States, residing at Franklin, in the county of Williamson and State of Tennessee, have invented certain new and useful Improvements in Back-Band Hooks; and I do hereby declare the following to be a full, clear, and exact description of the invention, such as will enable others skilled in the art to which it appertains to make and use the same.

This invention relates to improvements in back-band hooks; and it consists in the novel construction and arrangement of parts, as will be hereinafter fully explained, and more particularly pointed out in the claim appended.

The annexed drawings, to which reference is made, fully illustrate my invention, in which—

Figure 1 represents a front view of my improved hook; and Fig. 2 is a side view of the same.

Referring by letter to the accompanying drawings, A designates the hook, the broad frame portion of which is provided with longitudinal slots a a, between which is a central bar, b, having downwardly-projecting spurs c, which enter the back-band and securely but removably connect the hook thereto.

Depending from the central portion of the lower bar, d, is the supporting-hook e, for the trace or chain f. This hook tapers from the points g g to the upwardly-curved end h, which latter has an enlarged end or knob, i, and is arranged above a tongue, j, between which is formed a passage, k, or an indirect inlet and outlet for the link of the chain. This tongue curves downwardly and forwardly, as at l, and

by such curvature serves to guide the link into the opening m, and said tongue also has an enlarged portion, n, in the rear of which the opening extends upwardly, and the tongue, being directly in rear of the hook aforesaid, forms vertical indirect passages for the chain-link, which, when slackened, cannot be accidentally displaced therefrom, as the same would either pass up behind the tongue or come in contact with the knob on the hook, thus throwing said link back in its proper place.

It will be seen that the parts herein set forth are constructed integral, and the thickened tapering hook portion strengthens said hook from the base to the lower bar of the frame, where the same is most needed, thus rendering the hook durable. At the same time it is cheap to manufacture.

What I claim is—

As an improved article of manufacture, the within described back-band hook, consisting of the frame A, having the spurs e, the downwardly-tapering hook e, having the end knob, i, and provided with the tongue j, curved, as described, and having the enlarged end n, and arranged directly in rear of the hook, whereby an indirect passage is formed, as shown, and the whole constructed integral, as and for the purpose set forth.

In testimony whereof I affix my signature in presence of two witnesses.

ALBERT DENNIS.

Witnesses:

JOHN WATSON,
J. J. SMITH.
